US00D585382S

(12) **United States Design Patent**
Kudo

(10) **Patent No.:** **US D585,382 S**
(45) **Date of Patent:** **** Jan. 27, 2009**

(54) **ELECTRICAL CONNECTOR**

(75) Inventor: **Tsutomu Kudo**, Tsukuba (JP)

JP 1259612 11/2005

(73) Assignee: **Tyco Electronics AMP K.K.**,
Kanagawa-ken (JP)

(**) Term: **14 Years**

(21) Appl. No.: **29/302,555**

(22) Filed: **Jan. 18, 2008**

(57) **CLAIM**

The ornamental design for an electrical connector, as shown and described.

DESCRIPTION

FIG. 1 is a front elevation view of an electrical connector, wherein broken lines show visible environmental structure showing my new design;

FIG. 2 is a top plan view thereof wherein broken lines show visible environmental structure;

FIG. 3 is a bottom plan view thereof wherein broken lines show visible environmental structure;

FIG. 4 is a right side elevation view thereof wherein broken lines show visible environmental structure;

FIG. 5 is a left side elevation view thereof wherein broken lines show visible environmental structure;

FIG. 6 is a rear elevation view thereof wherein broken lines show visible environmental structure;

FIG. 7 is a top, front and right side perspective view thereof wherein broken lines show visible environmental structure; and,

FIG. 8 is a bottom, rear and left side perspective view thereof wherein broken lines show visible environmental structure.

The broken lines of the internal elements of the connector in FIGS. 1 and 6 are included to show unclaimed subject matter only and form no part of the claimed design.

1 Claim, 8 Drawing Sheets
